Byrnes, Robbins & Mandel

UNITED STATES PATENT OFFICE

THOMAS L. WHITE, OF YOUNGSTOWN, OHIO, ASSIGNOR TO THE COMMERCIAL SHEARING AND STAMPING COMPANY, OF YOUNGSTOWN, OHIO, A CORPORATION OF OHIO

SUPPORTING BRACKET

Application filed October 15, 1927. Serial No. 226,335.

The present invention relates broadly to supports, and more particularly to a supporting bracket of such nature as to be especially useful in the supporting of lavatories and similar fixtures. It has heretofore been customary in the art to which this invention relates to provide cast metal brackets which, besides being unnecessarily heavy, are objectionable by reason of the fact that if tightly attached to an uneven surface in such manner as to provide a firm support, they not infrequently crack or fracture.

The present invention provides an improved supporting bracket, of extremely light weight, and having the desired strength and rigidity, coupled with a sufficient degree of flexibility to permit the same to be efficiently used, irrespective of irregularities in the contour of the surfaces to which it is attached.

20 In the accompanying drawings there is shown for purposes of illustration only, a preferred embodiment of the present invention, it being understood that the drawings do not define the limits of my invention, as 25 changes in the construction and shape of the respective parts may be made without departing either from the spirit of the invention or the scope of my broader claim.

In the drawings:

30 Figure 1 is a side elevational view, partly broken away, showing my improved bracket in position on a supporting surface;

Figure 2 is a transverse sectional view on the line II—II of Figure 1, looking in the direction of the arrows, and,

Figure 3 is a vertical sectional view on the line III—III of Figure 1, looking in the direction of the arrows.

In accordance with the present invention, 40 there may be provided a supporting member 2, preferably formed of sheet metal, and having substantially a channel shaped cross section. The supporting member, when so shaped, provides a bottom portion 3 and a 45 side portion 4. Each of the side portions is preferably provided with laterally extending flanges 5, provided with openings 6 for the reception of screws or other securing means 7, for attaching the supporting member to a supporting surface S.

The bottom portion 3 of the supporting member is conveniently formed with a series of openings 8 of elongated form adapted for the reception of spaced lugs 9, formed on the sides 10 of a channel shaped bracket arm 11. 55 The bracket arm is likewise preferably of sheet metal, pressed to the desired shape to provide tapered sides 10 and to provide one or more openings 12 in the bottom portion 13 for the attachment of the lavatory or the 60 like to the bracket.

It will be apparent to those skilled in the art that by providing lugs 9 on each of the sides 10, there is created a substantial area of contact between the supporting member 65 and the bracket arm, the actual points of engagement being sufficiently spaced to prevent relative twisting or bending movement between the respective parts. This constitutes 70 one of the advantages of the present invention.

Further advantages arise from the provision of a supporting bracket constructed entirely of sheet metal whereby the desired strength is obtained with a minimum weight 75 of material.

Still further advantages arise from the provision of a supporting member and a bracket arm, both of channel shape in cross section and so constructed that the parts when 80 inter-engaged provide a substantial area of contact therebetween.

Other advantages of the invention are inherent in the use of a flexible supporting arm adapted to conform to an irregular supporting surface, without liability of cracking or 85 fracturing.

I claim:

As an article of manufacture, a supporting bracket comprising a pressed metal supporting member of channel shaped cross section adapted to be secured to a supporting surface and provided with a plurality of openings spaced transversely and vertically of 90 said supporting member in the bottom thereof, and a sheet metal bracket arm of channel shaped cross section, each of the side flanges of the bracket arm having projections thereon at the top and bottom of the flanges and lying 95 in the plane of the flanges, said projec- 100

tions being adapted to engage said spaced openings, the web of the channel shaped bracket arm between the side flanges thereof being several times wider than the thickness of the side flanges so that the web cooperates with the supporting member between the transversely spaced openings to provide lateral stability for the supporting bracket.

5 In testimony whereof I have hereunto set my hand.

10
